Patented Dec. 20, 1921.

UNITED STATES PATENT OFFICE.

CONRAD JURKOVICH, OF JOLIET, ILLINOIS, ASSIGNOR OF FORTY PER CENT. TO
PHILLIP HIBLER, OF JOLIET, ILLINOIS.

CONVERTIBLE BENCH.

1,401,083.

Specification of Letters Patent. Patented Dec. 20, 1921.

Application filed January 9, 1920. Serial No. 350,265.

To all whom it may concern:

Be it known that I, CONRAD JURKOVICH, a citizen of the United States, residing at Joliet, in the county of Will and State of Illinois, have invented certain new and useful Improvements in a Convertible Bench, of which the following is a specification.

This invention relates to combined seats and tables, and has for one of its objects to improve and simplify the construction and increase the efficiency and utility of devices of this character.

Another object of the invention is to provide a simply constructed device of this character which may be quickly transformed from a bench or seat into a combined table and seat, without detaching any of the parts.

With these and other objects in view, the invention consists in certain novel features of construction as hereinafter shown and described and then specifically pointed out in the claims, and in the drawings illustrative of the preferred embodiment of the invention.

Figure 1 is a perspective view of the improved device arranged as a combined seat and table.

Fig. 2 is an enlarged sectional detail of the spring controlled brace catch.

Fig. 3 is a transverse section on the line 3-3 of Fig. 2.

Fig. 4 is a transverse section showing the parts arranged to form a seat.

Fig. 5 is a transverse section showing the parts arranged to form a combined table and seat, and likewise illustrating a modification in the construction.

Fig. 6 is an end elevation showing two of the devices arranged to form a double sized table with a seat at each side.

Fig. 7 is an enlarged sectional detail illustrating the arrangement of the table brace.

The improved device comprises a supporting frame, including vertical relatively long members or standards 10 and relatively short standards 11.

Any required number of the standards 10 and 11 may be employed, depending on the length of the device, but for the purpose of illustration two sets are shown which will be sufficient for an ordinary length of device.

At its ends the device is provided with supports 12 attached at their edges to the

standards 10 and 11, and each with an opening, as shown.

A seat member 13 is attached at its rear edge to the standards 10 and bears at its forward portion upon the shorter standards 11, and the forward portions of the end supports 12.

At its ends the seat 13 is cut away to form relatively large recesses, and the cut away portions replaced by filler members 14 hingedly united at 15 to the body of the seat, as shown. The recesses of the seat and the filler members 14 are preferably angular in outline and the latter are supported at their free pointed ends upon the rear portions of the supports 12. The filler members 14 are movable upwardly, the object to be hereafter explained.

Hingedly united at 16 to the upper ends of the standards 10 is a combined back and table top 17, the latter foldable into horizontal position as shown in Figs. 1 and 5 and into substantially vertical position in front of the standards 10 as shown in Fig. 4.

Attached to the table member 17, at each end, is a cleat 18 extending below the lower line of the top, and attached to the member 17 in spaced and parallel relation to each of the cleats 18 is another cleat 19, the cleats forming guards for braces 20 which are pivoted between the cleats at one end, as shown at 21. When not in use, or when the top 17 is arranged as shown in Fig. 4, the braces 20 will be folded against the face of the seat and between the cleats.

Each of the members 10 is formed with a seat or recess 23 to receive the free ends of the braces 20 when arranged as shown in Fig. 1.

The braces 20 thus operate to maintain the table top member 17 in horizontal position, as shown in Fig. 1, or permit the same to be disposed substantially in vertical or folded position as shown in Fig. 4.

Thus when the device is to be used as a bench or seat only, the top member 17 and braces 20 are disposed in collapsed or folded position, and when required as a combined table, and seat, the transformation can be quickly accomplished as before described with the braces bearing at the free ends in 105 the seats 23.

The standards 10 are connected near their upper ends by a rail 22 and their lower ends

by a rail 24, and stays 25 are arranged to bear at their lower ends upon the rail 24 and support the seat 13 intermediate its ends. Secured to the ends of each of the cleats 18 and 19 farthest from the pivots 21 is a spring pressed catch device represented as a whole at 27, each including a rib 28 to enter a socket or seat in the free ends of the braces 20, to hold the latter yieldably in locked position when not in use, or when the top member 17 is arranged as a back for the seat, as shown in Fig. 4.

A conventional construction for the catch device is shown in detail in Figs. 2 and 3.

When arranged as a combined seat and table, the movable portions 14 of the seat, enable the intending occupants of the seat to very easily and readily pass thereto without the necessity of climbing over the seat.

This is a convenient feature of the device and adds materially to its value and efficiency.

Foot boards 26 are arranged next to the end supports 12, to facilitate the entrance of the intending occupants of the seat thereto.

Two of the improved devices may be arranged back to back as shown in Fig. 6, with the meeting edges of the table top members 30 coupled by hooks 23, or other suitable fastening devices, if required, to form a table of double size.

In Fig. 5 a modified form of the brace 20 is shown, which may be employed instead of the brace structure shown in Figs. 1 and 6. The modified braces are pivoted at 30 in a keeper 31 on the longer standards 10 and engage by their free ends in a stop 32 on the lower face of the top 17. When

not in use the braces hang in parallel relation to the standards 10 as shown in dotted lines.

Having thus described the invention, what is claimed as new is:

1. A device of the class described, comprising a supporting frame, a seat supported at one edge from said frame, end supports at the terminals of said seat and attached to the frame, a combined back and table top swinging from said frame, cleats in spaced relation attached to the table top, and braces swinging at one end between the cleats and concealed thereby when withdrawn and adapted to engage at their free ends against the frame when projected and maintaining said table top in horizontal position. 45

2. A device of the class described comprising a supporting frame, a seat attached at one edge to said frame and having movable end portions, end supports at the terminals of said seat and attached to the frame, said end supports having recesses providing access to the spaces produced by the movable portions of the seat, and a combined seat back and table top supported by 65 said frame.

3. A device of the class described, comprising a supporting frame, a seat supported at one edge from said frame, said seat having recesses at its ends, filler members movably disposed in said recesses, a combined seat back and table top swinging from said frame, and braces supporting said table top from the frame. 70

In testimony whereof, I affix my signature 75 hereto.

CONRAD JURKOVICH.
